ATTORNEY.

UNITED STATES PATENT OFFICE.

DE WANE B. SMITH, OF DEERFIELD, NEW YORK.

DESIGN FOR A SPRAYER-BODY.

SPECIFICATION forming part of Design No. 29,900, dated December 27, 1898.

Application filed December 5, 1898. Serial No. 698,383. Term of patent 7 years.

To all whom it may concern:

Be it known that I, DE WANE B. SMITH, a citizen of the United States, residing at Deerfield, in the county of Oneida and State of New York, have invented and produced a new and original Design for Sprayer-Bodies, of which the following is a specification, reference being had to the accompanying drawings, forming a part thereof.

Figure 1 shows a side elevation of a sprayer-body of my present design. Fig. 2 shows an end view of the same. Fig. 3 shows a perspective view of the same.

The feature of the design consists in the form, shape, and arrangement of parts constituting the body, as follows: the elongated

cylindrical portion 1 and the depending inverted conical portion 2, arranged at one end of the portion 1, all as shown in the drawings.

Having described my invention, what I claim as new, and desire to secure by Letters Patent, is—

The design for a sprayer-body as herein shown and described.

In witness whereof I have hereunto set my hand, in the presence of two witnesses, this 30th day of November, 1898.

DE WANE B. SMITH.

Witnesses:

SARAH A. BROWN,
E. WILLARD JONES.
